CLAIM

The ornamental design for a hand-held control unit for the operation of an inflatable air mattress, as shown and described.

DESCRIPTION

FIG. 1 is a perspective view of a hand-held control unit for the operation of an inflatable air mattress showing my new design;

FIG. 2 is a top plan view thereof;

FIG. 3 is a side elevational view thereof, the opposite side being a mirror image of that shown;

FIG. 4 is a bottom plan view thereof;

FIG. 5 is an end elevational view thereof; and

FIG. 6 is an opposite end elevational view thereof.

FIG. 1

FIG. 2

FIG. 3

FIG. 4

FIG. 5

FIG. 6
